UNITED STATES PATENT OFFICE.

JACK M. BOOTH, OF AMERICAN FALLS, IDAHO.

POST OR POLE.

1,089,459.

Specification of Letters Patent. Patented Mar. 10. 1914.

Application filed April 8, 1913. Serial No. 758,573.

To all whom it may concern:

Be it known that I, JACK M. BOOTH, a citizen of the United States, and a resident of American Falls, in the county of Power and State of Idaho, have invented a new and useful Improvement in Posts or Poles, of which the following is a specification.

My present invention relates to posts or poles, my object being to provide a metallic post which may be quickly and economically formed, which will effectually receive and hold longitudinal fence wires and thus be adapted for use as a fence post, and which may be driven into the earth and rigidly maintain itself in position.

Further objects, and the advantages of my present construction will appear in the course of the following description, in which reference is made to the accompanying drawing, forming a part of this specification, and in which—

Figure 1 is a side elevation of the post blank, the preliminary operation of bending the angular portions of the plate having been completed, Fig. 2 is a front elevation of the completely formed post, illustrating its practical application, Fig. 3 is a side elevation of the completed post as shown in Fig. 2 with its upper portion broken away and in section in order to better illustrate the fence wire fasteners, and Fig. 4 is an enlarged cross section taken through the post substantially on the line 4—4 of Fig. 2, and looking downward.

Referring now to these figures, the blank of my improved fence post is formed of an elongated strip of sheet metal, the upper end of which is squarely cut off, and the lower end of which is tapered to a point located in the median plane of the strip.

In the preliminary operation of forming the posts, the strip is bent along its median longitudinal line, in order to form angular portions A and A' as shown, the pointed lower end being indicated at a, and provided with a plurality of apertures a', extending in a series from a substantially central point to its upper end and located along the line of angle between the said portions A and A', each of these apertures forming transverse slots in the outer face of the post into which the longitudinal wires B of a fence may project, it being thus easy to secure these fence wires B by the use of 55 U-shaped fasteners C, as particularly indi-

cated in Figs. 3 and 4, which straddle the fence wires and have their extremities spread apart upon the inner surface of the post after being extended through the apertures a', before mentioned.

Adjacent to the lower end of the post the angular portions A and A' are provided with lateral extensions or wings D and D', at the upper ends of which are formed longitudinally extending prongs d, the inner sides of which are separated from the sides of the said angular post portions, the said wings being bent, following the bending of the angular post portions, to lie in substantially the same plane, and the prongs d being curved forwardly and downwardly in order that their sharpened ends may extend into the soil and form lateral supports for the posts when the latter is driven into the ground. Below the prongs d, the angular portions A and A' are provided with downwardly diverging slits e, in order to form integral tongues E, which are bent to flare forwardly and outwardly with respect to the posts in order to resist upward movement of the post after it has been driven into the ground as before described.

Thus from the foregoing it may be readily seen that the operations incident to the formation of my improved fence posts are comparatively simple and inexpensive and that the structure which I provide necessitates the use of a comparatively small section of metal plate. It will further be seen that when the fence post is driven into the ground the upwardly and outwardly flaring tongues E will resist any tendency toward upward movement of the posts, and will quite naturally coöperate with the downward bent prongs d to laterally support the post.

I claim:—

1. A post blank composed of an elongated plate of metal bent longitudinally upon itself to form two wings at an angle to each other, the said plate having its wings provided at their lower ends with lateral extensions and having the upper ends of said extensions separated at their inner edges from the body of the post to form projecting tongues, said tongues being tapered to form outer pointed ends and being bent downwardly so as to enter the surface of the ground, the said wings being also slotted below said tongues to form tongues free at their upper ends, the

- lateral extensions being adapted to be bent out of the plane of the wings from which they project, substantially as set forth.
2. A post comprising an elongated plate bent to form angular portions, the said angular portions being tapered and sharpened at their lower ends and being provided adjacent said lower ends with laterally projecting wings bent to extend in substantially the same plane and provided at their upper ends with downwardly bent prongs adapted to form lateral supports for the post as used.
3. A post of the character described, comprising an elongated plate bent along a longitudinal line to provide angular portions, the lower ends of said angular portions being provided with laterally extending wings bent to lie in substantially the same plane and provided at their upper ends with downwardly bent prongs, the said post being provided with a lower tapering sharpened end, and the said angular portions being slotted adjacent the lower end of the post in order to provide upwardly and outwardly flaring tongues adapted to resist upward movement of the posts in use, and to coöperate with the said wings and prongs to form lateral supports for the post, substantially as described.

JACK M. BOOTH.
